MICROPHONE HOLDER

Roy L. Huff, Eatontown, N. J., assignor to the
United States of America as represented by the
Secretary of War

Application March 5, 1945, Serial No. 581,011

2 Claims. (Cl. 179—146)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to microphone holders and more particularly to holders designed for mounting in portable equipment.

It has been the practice in the past to suspend hand-type microphones from a hook affixed to a vertical support such as the inside wall of a cabinet for housing portable transmitting equipment.

The above arrangement was satisfactory as long as the equipment was not being moved about. However, movement of the equipment for various reasons, would invariably dislodge the microphone with resulting damage to same.

It is therefore an object of this invention to provide a holding device which will retain a microphone rigid but still permit the immediate removal of said microphone from the holding device.

This and other objects will be apparent from the context of the specification and the attached drawing.

Reference is therefor had to the following drawing:

Figure 1 is a front view of the invention showing a broken section of the felt ring through which can be seen the manner of affixing the finger-like spring holder.

Figure 2 is a partial cross section and side elevation showing the manner in which the finger-like spring holders are mounted within the invention.

Figure 3 is a pictorial view of a microphone mounted within the invention, the broken lines indicating the position of the finger-like spring holders with reference to said microphone.

Referring now more particularly to Figures 1 and 2, the invention comprises a cup-like member 10 having a rolled edge 16, the said rolled edge being reinforced and stiffened by the inclusion therein of annular wire member 17.

Within the cup-like member 10 and to the bottom thereof are riveted three finger-like members 11, 12, and 13 made of flat springy material which serve to maintain microphone 20 within the confines of cupped member 10. The material of the fingers 11, 12 and 13 should be such that when deformed by placing the microphone within their grasp, will not take a permanent set.

Finger member 11 is positioned diametrically above apertures 18. The placement of finger member 11 is such that its position in relation to

the inside edge of member 10 opposite to said finger represents a distance which would make a snug fit for microphone 20.

The other finger members 12, 13 are positioned radially the same distance as finger 11 but spaced from said finger 11 by an arc of 70° either side of said finger 11.

Cemented within and at the bottom of member 10 is a felt ring 14. The felt ring 14 also covers the base of the fingers 11, 12 and 13 and by these means protects the face of the microphone from injury by rivets 15 which fasten the fingers 11, 12 and 13 to the cupped member 10.

Referring to Figure 3, the cupped member 10 is fastened to a vertical support 21 such as the inside of a cabinet for housing the equipment, in conjunction with which the microphone 20 is used. The cupped member 10 is fastened to the supporting member 21 with bolts 19 placed thru apertures 18 provided in the bottom of the cupped member 10 as heretofore described.

Thus it can be readily observed from the drawing the manner in which the microphone 20 is retained securely in position by the fingers 11, 12 and 13 and by these means inhibiting motion of said microphone. Yet, withal, the microphone 20 is instantly available for use by a slight pull on the handle of same.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A microphone holder comprising a cup-like member including a cylindrical wall of greater diameter than a microphone to be used therewith and a circular base wall at one end thereof and provided with a rolled edge about the rim of the other end of the cylindrical wall, at least three spring fingers, each of which is positioned at least partly within said cup-like member, said fingers, when in their operative positions, being so disposed relative to one portion of said cylindrical wall that the said fingers and said portion are along the periphery of a circle of substantially the same size as said microphone, one of said fingers diametrically opposing said portion and the other two fingers being on opposite sides of said first finger and each being angularly removed from said first finger by substantially 70°, so that

said microphone may be resiliently gripped between said three fingers and said portion, each of said fingers being provided with an inclined surface against which the microphone slides while being inserted into said gripped position and a second inclined surface against which the microphone slides while being withdrawn from said gripped position, and a pad of resilient material secured to said base wall against which the microphone rests when in its said gripped position.

2. A microphone holder comprising a cup-like member including a cylindrical wall and a base wall at one end thereof and provided with a rolled edge about the rim of the other end of the cylindrical wall, spring finger means at least partly within said cup-like member and opposing one portion of said cylindrical wall so that a microphone may be resiliently gripped between said spring finger means and said portion of the cylindrical wall, said finger means being provided with an inclined surface against which a microphone slides while being inserted into said gripped position.

4
tion and a second inclined surface against which the microphone slides while being withdrawn from said gripped position, and a pad of resilient material secured to said base wall against which the microphone rests when in its said gripped position.
